UNITED STATES PATENT OFFICE.

HERBERT E. PICKETT, OF BALTIMORE, MARYLAND.

BASEBALL GAME BOARD.

Application filed April 14, 1927. Serial No. 183,698.

This invention relates to games and has particular reference to a game apparatus for playing baseball.

The primary object of the present invention is to provide a game apparatus whereby the game of baseball may be played on a miniature scale and under substantially the same rules as employed in the outdoor game, and wherein the outcome of the game will 10 depend largely upon the skill of the players, rather than upon chance.

Another object is to provide a game apparatus of this character which shall be constructed and arranged in such manner 15 that the pitcher may, at will, throw fast balls, slow balls, or curves, and the batter in turn may, at will, strike at the ball with full effort or bunt or with any intermediate effort and thus closely simulate the pitching and batting practice commonly employed 20 in outdoor games. In this manner the game is rendered particularly interesting as the skill and wits of the players are matched against each other and the game is in no 25 sense dependent upon chance in the sense that dice or similar chance devices are used.

A further object is to provide a game apparatus of the aforesaid character which shall be relatively small and compact so 30 that it may be supported on a table and be played by two or more players.

A still further object is to provide a game device embodying the aforementioned features which shall be simple in construction, 35 inexpensive to manufacture and which shall be easy to operate.

With these and other objects in view, the invention may be stated to consist in the various novel features of construction 40 and arrangement or combination, all of which will be fully described hereinafter and pointed out in the appended claims.

In the drawings forming part of this application:

Fig. 1 is a top plan view of an apparatus embodying my invention;

Fig. 2 is a perspective view of two of the field pieces used in playing the game;

Fig. 3 is a similar view of a still further 50 type field piece used;

Figs. 4 and 5 are transverse sectional views taken respectively on the lines 4—4 and 5—5 of Fig. 1;

Fig. 6 is a front elevation of the batting 55 device;

Fig. 7 is a detail front elevation of a

target employed during certain plays in the game.

Fig. 8 is a transverse sectional view taken 60 on the line 8—8 of Fig. 1;

Fig. 9 is a fragmentary detail top plan view of the batting corner; and

Fig. 10 is a fragmentary side elevation 65 thereof, as viewed from the left-hand side of Fig. 9.

A game apparatus constructed in accordance with my invention consists of a substantially rectangular box-like structure having a bottom 1, sides 2 and ends 3, such elements being reinforced at their meeting 70 ends or at the corners defined by such ends, by posts 4 which rise from the base 1 at three of the corners and terminate slightly below the upper edges of the sides 2 and ends 3 for a purpose to be referred to hereinafter. 75 The other corner is reinforced by a post 4^a, as clearly shown in Figs. 1 and 4, which depends downwardly from the upper edges of the sides and ends and terminates short of the bottom plate 1.

Arranged directly above the bottom plate 1 is an inclined floor 5 which slopes from each corner defining first and third bases to a central line intersecting second and home bases, as shown in Fig. 5, and this floor 85 is also inclined in its entirety from the corner defining second base toward the pitcher's box, as shown in Fig. 4. The function of this floor, as will become more apparent hereinafter, is to return the ball to the corner 90 below the pitcher's box by gravity.

Secured directly above but spaced from floor 5 is a horizontally disposed platform 6 which serves as the field or diamond, and upon which the game is played. As shown 95 particularly in Figs. 4 and 5, this platform is located below the upper edges of the sides 2 and ends 3 so that the latter may act as back stops for a ball pitched or batted, and thus serve to confine the ball to the 100 box-like structure. By referring to Fig. 1, it will be noted that the platform forming the field or diamond is recessed along the edges normally abutting the sides and ends of the box as indicated at 8, 9, 10 and 11, thus permitting the ball, under certain conditions of play, to drop through these recesses and onto the inclined floor 5 where it will be returned by gravity to the corner 105 below the pitcher's box. In practice, I preferably form this platform with a slight concave surface so that when a ball is pitched 110

slowly or rolls slowly from the pitcher's box towards home plate it will travel in a slightly curved path, due to the resultant force from the inertia of its normal direction of travel and the force of gravity acting thereon by virtue of the slight concavity aforementioned. This concavity is, however, preferably of a very slight degree so that a fast ball will not be affected thereby.

10 A pitching device is located in one corner of the box and consists of an arm 13 pivoted intermediate its ends at 14 to the platform 6. One end of this arm has connected thereto a rubber or elastic band 15 which in turn 15 is detachably connected at its opposite end to a hook 16 that is fastened to post 4. The elastic band 15 is formed with a knot 18 intermediate its ends so that under certain conditions, the tension on arm 13 may be increased by securing the knotted portion of the band over the hook 16. The opposite end of the pitching arm is recessed at 19 to receive therein the ball to be pitched. Cooperating with the pitching arm, to determine the type and direction of the ball to be pitched, is a cam plate 20 which is adjustably and eccentrically pivoted at 21 to the platform 6 by a screw and wing nut 22. This cam plate is preferably formed 25 with two sides 23 and 24 defining substantially a right angle, and with a rounded toe portion 25 connecting the ends of such sides. As indicated in dotted lines in Fig. 1, the cam plate is adjustable about its pivot to 30 limit the swing or throw of the pitching arm when retracted manually and released under the tension of the elastic band 15. The specific operation of the pitching arm will be described more fully hereinafter.

35 Located in the diagonally opposite corner of the box is a batting device consisting of an arm 28 which is pivoted between the spaced knuckles of a bifurcated block 29 that is fastened to the platform 6. As clearly 40 shown in Fig. 6, this batting arm is pivotally connected to the block and platform by a bolt 30 extending therethrough and fitted with a nut 31. The arm 28 is formed at its outer end with an enlarged portion 32 that 45 extends below the arm proper and is of a width substantially equal to the home plate indicated at 33. A spring 34 fastened at one end to block 29 and normally engaged at its other end with the arm 28 tends 50 normally to urge said arm toward the pitcher's box. The arm is retracted against the tension of the spring by a flexible cord or wire 35 that is fastened at one end to the outer end of the arm, while the opposite end 55 of the flexible element extends through an opening 36 in the end wall 3 and is fitted with a knob or handle 37. The upper surface of the block 29 may be recessed to receive a plurality of balls 38 which serve as 60 players or runners while the game is being

70 played and thus provide a readily accessible place therefor. A vertically disposed barrier 40 projects from end wall 3 between third base and home plate and a similar barrier is located between first base and home plate and these elements define the foul lines.

75 Formed adjacent the upper edge of the side wall 2 extending between first base and the home plate corner, and between third base and this corner is a runway consisting of an open top trough 41 of a width and height substantially equal to the diameter of the balls 38 which form players. This trough 80 also extends along the opposite side and end walls to a point adjacent the pitcher's box whereupon it is deflected diagonally across the corner forming the pitcher's box, as indicated at 42 in Fig. 1. Each of the three corners 4 is formed with a slight depression 85 43 and a similar depression is formed substantially midway of the diagonal position 42. These depressions form the three bases and home base for the players. Slidably mounted along the inner vertical wall of this trough is a tape 44 which is provided with pairs of laterally projecting blocks 45 that are adapted to receive therebetween a ball 38 constituting a player. The tape with 90 player or players in position therein may be advanced around the bases, step by step, manually by grasping the same at the station 46 where it will be noted that the side walls of the trough are recessed to afford a convenient grasp of the tape between the thumb and forefinger and permit limited 95 horizontal movement.

100 Depending from the diagonal portion 42 of the trough is a wall 47 having a rectangular recess 48 therein to expose the recessed end 19 of the pitching arm, as clearly shown in Fig. 5. Mounted adjacent the upper side edges of this wall are pivoted levers 49 and 50, each of which swings over a chart. The chart 51 is divided into three divisions to 105 represent strikes, while the chart 52 is divided into four divisions to indicate balls, and the levers are moved manually to facilitate 110 keeping account of the balls and strikes of each player at bat.

115 In order to indicate certain plays, I provide markers in the form of blocks 54, one of which is labelled II and the other III. These markers may be placed by the pitcher on any of the stations 55 formed on the diamond adjacent the pitcher's box, and a ball striking the same will indicate a hit, but if the block is knocked over by the batsman, the player is entitled to a two or a three base hit, depending upon the particular block 120 knocked over. A smaller marker 57 is also used and may be placed on either of the two stations 58 and this marker when knocked over by a batted ball will indicate a home run.

In use, two or any number of players up to eighteen may play the game. When more than two players participate, a captain is chosen and he may assign duties and arrange the batting and pitching order. It is preferable also that each player stay at bat until he is put out and also that no one player may pitch more than one inning in succession.

The sides having been chosen, the pitcher 10 places a ball, such as a marble, in the recess 19 of the pitching arm, having adjusted the tension of elastic band 15 and the position of cam plate 20. The arm 13 is now retracted manually and released, whereupon the ball 15 will travel toward home plate. If the cam is adjusted properly the ball may be made to travel directly over the home plate or to either side thereof, at the will of the player. The speed of the ball is controlled by the 20 tension of elastic band 15, and by substituting various weight elastic bands major, minor or bush league games may be played, depending on the proficiency of the players. Curves may also be pitched, as explained 25 heretofore. Meanwhile the batsman has retracted the batting arm 28 by pulling on string 35 and as the ball travels over the plate he may strike at it by releasing the string at the proper instant. By pulling 30 outwardly on string 35 to varying degrees, he may "slug" at the ball or "bunt," as he desires. When the batsman hits the ball or receives four balls, he advances a player 35 along the runway from home toward first base in the manner previously described. The depressions 43 at the bases cause the runner to stop automatically as the blocks 45 open slightly when they round the corners of the trough. At great speed, however, it is possible to overrun a base.

To put a man out at first, the defense must wait until the ball has rolled by gravity to the corner beneath the pitcher's box, where he reaches through an aperture 60 (Fig. 5) and picks up the ball and endeavors to place it in the first base depression before the runner reaches it. Of course, when bunting and the ball does not roll off the diamond, the defense may field it directly thereon. To put a man out at second base, the defense must shift the pitching cam adjustment to the shortest axis which will enable him to throw to a hingedly mounted target 61 mounted on the first base line. If this is hit before the runner reaches second base the runner is out. To put a man out at third base, the same procedure is followed as at first base. To put a man out at home, the pitcher must throw 60 the ball by means of the pitching arm across the home plate before the runner reaches home base.

Any ball hitting one of the foul wing markers 40 and rolling beneath the platform 65 or diamond is a foul ball; if however, the

ball rolls out upon the diamond after striking the foul marker, it may be fielded as a caught foul retiring the runner.

A ball pitched and passing the batter enters an opening 65 in the platform or diamond 6 at the catcher's corner and returns by gravity to the opening 60 beneath the pitcher's box, the latter opening being for convenience termed the "pitcher's glove." Stealing base may occur by a runner starting with the throw and endeavoring to get to the next base before the ball reaches the pitcher's glove and is touched to the base 70 stolen.

A small marker similar to that shown in Fig. 3 may be placed in the batter's box 66 by the batting side to simulate a player and if this marker is hit and knocked over by a pitched ball, the player takes his base. A ball hitting block 29 is a wild pitch.

When running bases, the marbles used as runners must be in the depression indicating the base or the defense may touch them out with the ball. A runner is allowed to be out of the depression on second base only as 90 this is, of course, directly over the pitcher's box. When there is more than one man on base, at least one man must be on the base proper while the others may be left in the running trough without danger of being put 95 out.

The pitcher indicates the balls and strikes on the indicators 49 and 50 on the front of the pitcher's box unless the players agree to have a third person act as umpire. In this 100 connection it will be noted, by referring particularly to Fig. 1, that I preferably provide scales or charts 70 and 71 along the inner edge of the trough portion 42 adjacent the levers 49 and 50 respectively so that the 105 pitcher may conveniently indicate the strikes and balls without looking at the charts 51 and 52.

It will be remembered that the runner is advanced around the bases by grasping the 110 tape between the fingers at the station 46 which requires a certain degree of skill due to the length of the opening in the trough wall, and this degree of skill closely resembles the ability of the runner as such, some 115 runners being faster than others while some players can manipulate their fingers faster than others.

The pitcher may rearrange the pieces 54 and 57 to meet the batting style of the particular batter, as in the outdoor game. That is, if the particular batter usually hits to right field, the pitcher may place the pieces in the left field position and thereby lessen the chances of a two or three base hit 120 or of a home run.

In some instances, as for example when stealing base, the batter may pull back on the flexible member 35 and unknown to the pitcher, engage the knob 37 in a depression 130

73 (Figs. 9 and 10) in the side wall 2 and then by jiggling the string with one finger he will move the bat 28, although when the opportune time comes his hand is free to 5 operate the tape 44, and when released from the string the bat will still be retracted and not count as a strike.

I claim:

1. A game apparatus of the character described comprising a box-like structure having a bottom, sides and ends, a platform defining a baseball field arranged intermediate said bottom and the top edges of said sides and ends, said platform being provided with 10 an opening at the catcher's box, and an opening intermediate adjacent bases, a pitching device in one corner of said structure and a batting device in the diagonally opposite corner, and means disposed below said platform for returning to the pitcher's corner the balls passing through said openings.
2. A game apparatus of the character described comprising a substantially rectangular box-like structure, a platform arranged 15 within said structure intermediate the top and bottom edges thereof and defining a baseball field, pitching and batting devices carried by said platform, said platform being formed with a plurality of recesses there- 20 in to afford communication therebeneath, and a floor arranged beneath said platform, said floor being disposed on an angle whereby a ball dropped thereon will roll by gravity to a point adjacent said pitching device.
3. A game apparatus of the character described comprising a substantially rectangular box-like structure, a platform arranged 25 within said structure and defining a baseball field, pitching and batting devices carried by said platform, said platform being slightly concave and provided with recesses 30 therein to afford communication therebeneath, and a floor arranged beneath said platform, said floor being sloped from the outer marginal edges to a central diagonal 35 line intersecting second and home bases and also sloped in its entirety from a point beneath home base to a point adjacent second base.
4. A game apparatus of the character described comprising a substantially rectangular box-like structure, a baseball field arranged 40 within said structure and carrying pitching and batting devices, a runway formed along substantially the perimeter of 45 said structure and defining a path for a runner, and an endless belt disposed in operative relation to said runway and having spaced projections for detachably receiving a runner 50 therebetween, said projections being adapted to separate when rounding a corner of said structure and eject the runner therefrom.
5. A game apparatus of the character de- 55 scribed comprising a substantially rectangu-

lar box-like structure, a baseball field arranged within said structure and carrying pitching and batting devices, a trough formed along substantially the perimeter of said structure and defining a path for a runner, said trough having depressions defining bases at definite intervals, and an endless belt arranged in operative relation to said trough and having a pocket for the reception of a runner, said belt being adapted to automatically eject the runner from said pocket upon passing a depression in said trough.

6. A game apparatus of the character described comprising a substantially rectangular box-like structure, a baseball field arranged within said structure and carrying pitching and batting devices arranged adjacent diagonally opposite corners of said structure, a trough arranged substantially along the perimeter of said structure but extending diagonally across the corner containing said pitching device, means for advancing a runner along said trough, and a plate depending from said trough in front of said pitching device, said plate having an opening therein to permit a ball to pass from said pitching device to said batting device.

7. In a game of the character described, a pitching device comprising a horizontally disposed arm pivoted intermediate its ends, to swing in a plane parallel with and adjacent to the plane of the game board, one end of said arm having a recess therein for the reception of the object to be thrown and the other end thereof being connected with a yielding element, and an adjustable abutment disposed in operative relation to said arm to limit the arc of swing under tension in a horizontal plane.

8. In a game of the character described, a 105 batting device comprising an arm pivoted for swinging movement, one end of said arm being enlarged to define a striking portion, a flat leaf spring engaged with one side of said arm and normally urging the same in a 110 direction about said pivot to strike at a ball, and a flexible element connected to said arm and adapted, when pulled, to place said arm under the tension of said yielding means.

9. A game apparatus of the character described comprising a substantially box-like structure, a baseball field within said structure, a batting device in one corner of said structure and a pitching device in the diagonally opposite corner thereof, said field having openings therein to permit a ball to pass therethrough by gravity, means for automatically returning the balls passing through said openings to the pitcher's corner, and a trough extending substantially 120 along the perimeter of said structure and defining a path for a runner.

10. A game apparatus of the character described comprising a substantially rectangular boxlike structure, a baseball field 130

arranged within said structure and carrying pitching and batting devices, a runway formed along substantially the perimeter of said structure and defining a path for a runner, and a flexible element disposed in operative relation to said runway for moving a runner therealong, said element being formed with lateral projections arranged in spaced relation and adapted to receive a spherical marker therebetween.

11. In a game of the character described, a pitching device comprising an arm pivoted to swing in a horizontal plane adjacent the game board and having a recess for the reception of an object to be thrown, yielding means connected to said arm and adapted when energized to move said arm to throw said object, means for varying the tension of said yielding means, and an adjustable abutment disposed in operative relation to said

arm and adapted to limit the swing thereof in a horizontal plane during its throwing stroke.

12. A game apparatus of the character described comprising a substantially rectangular boxlike structure, a base ball field arranged within said structure and carrying pitching and batting devices, a channel shaped runway having a bottom and sides formed along substantially the perimeter of said structure and defining a path for a runner, and a flexible element disposed in operative relation to said runway for moving a runner therealong, a side of said runway being recessed to expose said flexible element and thereby permit the operator to grasp said flexible element and move the same along said runway.

In testimony whereof I affix my signature.
HERBERT E. PICKETT.
